UNITED STATES PATENT OFFICE.

PETER M. BOECK, OF SOUTH BEND, INDIANA, ASSIGNOR TO THE MALLEABLE STEEL RANGE MANUFACTURING CO., OF SOUTH BEND, INDIANA, A CORPORATION OF INDIANA.

PILOT-LIGHTER.

1,073,321.

Specification of Letters Patent.

Patented Sept. 16, 1913.

Application filed September 20, 1912. Serial No. 721,399.

To all whom it may concern:

Be it known that I, PETER M. BOECK, a citizen of the United States, and resident of the city of South Bend, in the county of St. Joseph and State of Indiana, have invented certain new and useful Improvements in Pilot-Lighters, of which the following is a specification.

This invention relates to improvements in pilot lighters and refers more particularly to pilot lighters for use with gas ranges although not necessarily limited thereto.

Among the salient objects of the invention are to provide a construction in which the burners can be readily and instantly lighted from the outside of the range and with no danger or possibility of "back flashing"; to provide a construction of the above character which is provided with a separate mixing and ignition chamber so divided as to cause a back and forth traverse of gas in the pilot lighter; to provide a construction which insures of the gas being at all times plentifully supplied with air for mixing; to provide a construction in which the ignition gases pass freely along a pair of diverging arms or wings extending beneath the burners and which can escape freely therefrom at all times and points throughout the length of said wings; to provide a construction which can be readily applied to standard types of gas ranges or stoves and in general to provide an improved construction of the character referred to which is economically and simply manufactured.

The invention consists in the matters hereinafter described and more particularly pointed out in the appended claims.

In the drawings—Figure 1 is a top plan view of a pair of gas burners with my improved pilot lighter applied thereto; Fig. 2 is a side elevation of the construction shown in Fig. 1; Fig. 3 is a rear end elevation of my pilot lighter with the burner pipes shown in section; Fig. 4 is a transverse sectional view taken on lines 4—4 of Fig. 2 and looking in the direction of the arrows, but on an enlarged scale.

Referring to the drawings—1 and 2 designate a pair of foraminated burner pipes apertured as shown at 3, 3.

4 designates the main supply pipe, connected to the burners by branches 5 and 6 and controlled by suitable cocks 7. In a suitable aperture in the end wall 8 of the

stove or range is inserted my improved pilot lighter, designated as a whole 9. This pilot lighter comprises a pair of diverging wings or arms 10 and 11 and a main supply conduit 12. The latter is divided into a mixing chamber 13 and ignition chamber 14, by means of a horizontal bridge wall or baffle plate 15, the inner end of which terminates short of the rear end of the conduit as shown more clearly in Fig. 2. The mixing chamber 13 communicates at its front end with a gas supply pipe 16 controlled by a turn cock 17. Near its front end the mixing chamber 13 is notched or apertured as shown at 18 to provide an air inlet. The upper end of the ignition chamber 14 is longitudinally slotted throughout its length as shown at 19 to permit the escape of sufficient gas for ignition. The wings 10 and 11 diverge downwardly and outwardly as shown in Fig. 3, so that 75 their outer ends are adjacent the foraminated portions of the burners 1 and 2. At their upper ends these wings are each provided with a series of ports 20, 20 to permit free escape of gas from the wings. All of 80 these ports 20 above the wings are provided with an over-hanging ledge or flange 21 which extends throughout the full length of the wings. In order to readily secure the pilot lighter to the range, it is preferably 85 provided with a pair of lugs 22 which are fastened to the wall 8 by screw bolt 23.

The operation of the device is well understood. Gas is admitted by opening the urn cocks of the burner tubes and pilot lighter 90 and a match applied to the slot 19. This instantly lights the burners through the ports in the wings 10 and 11. The pilot lighter is then of course cut off. It will be noted that only a relatively small amount of 95 gas is permitted to escape through the slot 19 while the main supply of gas in the chamber 13 is thoroughly mixed with the incoming air before the gas is ignited. The back and forth traverse of the gas as well as 100 the provision for its free escape through the wings prevents any back flash which is the chief difficulty and danger with pilot lighters.

The invention is not limited to the details 105 of construction shown except as set forth in the appended claims.

I claim as my invention:

1. A pilot lighter comprising a main inlet conduit, a baffle plate dividing said conduit 110

into a mixing chamber and an ignition chamber, said former chamber having an air inlet and said latter chamber being longitudinally slotted at its upper end, and a pair of diverging arms connected to the inner end of said main conduit, each arm being provided with a plurality of ports at its inner face and having a flange overhanging said ports.

2. A pilot lighter comprising a main inlet conduit, a pair of diverging arms connected to the end of said main conduit, a baffle plate extending from the entrance end of said main conduit to within a short distance

of said arms for dividing said main conduit into a mixing chamber and an ignition chamber, an air inlet for the mixing chamber, the upper wall of said main conduit having an ignition outlet from said ignition chamber and said arms having each ignition outlets through their inner walls, and a flange on each arm overhanging the ignition outlets therethrough.

PETER M. BOECK.
